J. H. McCaughan
ATTORNEY

UNITED STATES PATENT OFFICE.

OSCAR NYGAARD, OF SAUGUS, MASSACHUSETTS, ASSIGNOR TO BERNITZ FURNACE APPLIANCE COMPANY, OF BOSTON, MASSACHUSETTS, A CORPORATION OF MASSACHUSETTS.

FURNACE WALL AND BRICK THEREFOR.

Application filed July 16, 1925. Serial No. 44,030.

This invention relates to furnace walls and to bricks for use in the construction of such walls.

The walls of furnaces which are subjected to sustained operation at high temperatures frequently become so hot that the surface of the wall softens or becomes plastic so that the slag and ash in the fuel bed sticks to it. When this fused mass is removed a part of the furnace wall is chipped off with it. As this action is repeated during the running of the furnace the wall is rapidly worn away until it reaches the point where it must be renewed. It has been found that this action can be obviated and the life of the furnace wall very materially increased by admitting air to the fuel bed through the part of the furnace wall which is liable to fuse. Such a construction is shown in Patent No. 1,393,606, granted October 11, 1921.

The present invention is especially, although not exclusively, concerned with the general type of furnace wall shown in the patent just mentioned, and it aims to improve this construction with a view to further increasing its effectiveness. It is also an object of the invention to devise a brick which can be advantageously used in furnace constructions wherever it is desired to cool the walls or any area of a furnace by air, as for instance, in pulverized fuel furnaces where it is found desirable to admit air through the furnace walls or portions thereof.

In the drawings,

Figure 1 is a vertical cross-sectional view through a portion of a furnace having walls constructed in accordance with this invention;

Fig. 2 is a horizontal, cross-sectional view on the line 2—2, Fig. 1;

Fig. 3 shows a portion of the structure illustrated in Fig. 2 but on a larger scale; and

Figs. 4 and 5 are perspective views of bricks embodying features of the present invention.

The furnace shown in Fig. 1 includes front, bridge and side walls and is equipped with an underfeed stoker including a hopper 2, ram 3, and grates 4, the stoker parts being constructed and arranged in the usual manner.

Referring to Fig. 2 it will be seen that the side wall of the furnace includes a rear section 5 and a front section or facing 6, an air space 7 being provided between these sec-

tions. Usually the rear section 5 is made of ordinary brick, while the front section or facing is made of fire brick, or other refractory material and in the construction shown the front facing is vertically corrugated.

The portion of the side wall shown in Figs. 1 and 2 is made up chiefly of bricks of the character shown on a larger scale at B in Figs. 3 and 4. Referring to the latter figures it will be seen that the central portion of the brick B is bulged forwardly, as shown at 8, or, in other words, it has a vertical rib which forms the central portion of the brick. The back of the brick is recessed or grooved opposite the rib or bulged portion, as shown at 9, so that in horizontal cross section the brick is of approximately V-shape with extended wings. Air holes 10 and 12 extend through the bulged or rib portion 8 of the brick from the recess 9 to the front face thereof, these holes preferably being oppositely directed, and they open on to the front face substantially at the base of the bulge or rib 8.

Air under pressure is forced into the space 7 between the front and rear sections of the wall and flows through the holes 10 and 12 into the fuel bed or into the interior of the furnace immediately adjacent to the fuel bed. The holes 10 and 12 are directed laterally so that they discharge air along the front surface of the facing 6, this air flowing across the surface of adjacent bricks and being diffused by its contact with the corrugated surface of the facing. Each brick, therefore, is cooled partly by the air which flows through it and partly by the air which is directed across its face from the holes in neighboring bricks. This arrangement thus tends to maintain a relatively cool "air curtain" immediately in front of the facing 6 and thus keeps this facing sufficiently cool to prevent slag and clinker from sticking to it. It will be seen from an inspection of Figs. 1 and 4 that the air holes in each brick are staggered or offset vertically with reference to each other so that a more uniform distribution of the air is produced.

The air which is discharged into the fire box through the wall is utilized in maintaining combustion, but only a relatively small part of the air required for combustion is discharged into the furnace in this manner, the greater part of the air for combustion

purposes being delivered through air conduits, such as that shown at 14 Fig. 1.

In building the furnace wall the bricks B above described are laid in courses, as shown in Fig. 1, with the V-shaped sections of superposed bricks in vertical alinement so that they form a vertically corrugated face. The upper corners of each brick are notched, as shown at 16, Fig. 4, to receive the bricks C which bond the facing 6 to the rear section 5 of the wall.

It usually is preferable to build only that portion of the wall which is subjected to highest temperature of the bricks shown in Fig. 4. 15 Adjacent portions of the facing which are not subjected to excessive temperature may advantageously be built of brick of the same general construction as that shown in Fig. 4 but without the air holes. This is true, for 20 example, in the upper portion of the bridge wall where the bricks 18 are like those shown in Fig. 4 except that they are imperforate. Here the corrugated construction of the brick is of advantage in producing a wall which 25 is stronger mechanically and is particularly effective in resisting the stresses set up in the wall by construction and expansion. The bridge wall, like that above described, has a space between the front and rear sections 30 through which air is circulated to keep the temperature of the facing within reasonable limits. At the bottom of this wall I prefer to use bricks of the construction shown in Fig. 4 and to blow air through them, as above 35 stated, in connection with the description of the side wall.

It is usually necessary to ventilate or air cool only a small part of the front wall, as shown in Fig. 1. Where the wall rests on a 40 girder, as does a part of the front wall, or where it is desired to change the surface of the facing from a corrugated to a plain contour, a brick of the type shown at 20 in Fig. 5 may conveniently be used. The upper part 45 of this brick is like the brick B in horizontal cross section, but the lower part is of approximately rectangular form in horizontal outline with an inclined face 21 leading downwardly from the notched corners 16—16. 50 The rear groove or recess 9 preferably extends the entire height of the brick, although, if desired, this recess can be stopped at any desired point. Such a brick has a flat bottom face to rest on a girder, brick wall, or the 55 like, and an upper face which fits the corrugated bricks of the type shown in Fig. 4. Bricks of this character are shown at 20 in Figs. 1 and 2, and they may or may not be provided with air holes 10 and 12, as desired. 60 The bricks provided by this invention may be made of carborundum, fire clay, or any suitable refractory material. A furnace wall in which these bricks are used has the advantage of being unusually strong mechanically while at the same time permitting the

air cooling which is so desirable for the reasons above described. Furthermore, the air is so directed that the maximum effectiveness of a given volume of air is realized in reducing the temperature of the wall facing. 70

While I have herein shown and described the best embodiment of my invention that I have so far devised, it is contemplated that the invention may be embodied in other forms without departing from the spirit or scope 75 thereof. Bricks embodying this invention may also be used in other parts of the furnace, as for example, in the construction of a cooling zone in the lower part of the furnace. Also, while I have chosen to illustrate my 80 new form of brick as it may be used in an underfeed stoker furnace to prevent clinkering in the side walls at the fuel bed area, it should be understood that the brick is not limited to use in furnaces of this character or 85 for the particular purpose of avoiding clinkering. The brick construction provided by this invention is designed for use in any furnace or heater where it is desired to cool the 90 walls, or area of any sort, by air.

Having thus described my invention, what I desire to claim as new is:

1. A furnace wall comprising a rear section and a vertically corrugated front section with an air space between said sections, and laterally directed holes leading from said air space through said front section to the front surface of the wall.

2. A furnace wall including a rear section, and a front section of bricks laid in courses, the bricks in superposed courses having approximately V-shaped sections vertically alined with each other to form a corrugated face on said front section, said bricks having notched corners, and tie bricks located in said corners and connecting said front and rear sections together.

3. A furnace wall including a rear section and a front section of bricks laid in courses, the bricks in superposed courses having approximately V-shaped sections vertically alined with each other to form a corrugated face on said front section, said bricks having notched corners, tie bricks located in said corners and connecting said front and rear sections together, and laterally directed air holes leading through said front section and arranged to direct air along the front face thereof approximately parallel thereto.

4. A brick for furnace wall construction comprising a body portion of refractory material with an outwardly bulged front, a rear face recessed opposite said bulged front, and one or more laterally directed air holes leading from the recess in said back through the 115 wall of the brick to the face thereof.

5. A brick for furnace wall construction comprising a body of refractory material with a rib projecting forwardly from the front face of said body, the rear surface of 130

- said body being recessed opposite said rib, and oppositely directed air holes leading from said recess through the wall of the brick and opening on to the face thereof at opposite 5 sides of said rib.
6. A brick for furnace wall construction comprising a body portion of refractory material with an outwardly bulged front, a rear surface recessed opposite said bulged front, 10 and oppositely directed air holes leading laterally from said recess through the wall of said bulged portion to opposite sides thereof, said holes being offset with reference to each other.
- 15 7. A furnace wall comprising a rear section and a front section of bricks laid in courses, said bricks in adjacent courses having approximately V-shaped sections alined with each other and projecting forward to form a 20 corrugated face on said front section, said V-shaped sections having air holes therethrough.
8. A brick for furnace wall construction comprising a body portion of refractory material having an outwardly bulged front and a rear face recessed opposite said bulged front; and a straight laterally directed air hole extending through said brick from said recess to the base of said bulged portion.
- 25 9. A brick for furnace wall construction comprising a body of non-metallic refractory material having a recess in the rearward part thereof and a projecting front face portion, and an air hole leading from said recess to a laterally facing portion of the front face of the brick, said hole being directed laterally of the brick, whereby it will discharge air across the face of another brick located immediately beside it.
10. A brick for furnace wall construction comprising a body of non-metallic refractory material having a ridge projecting from the front face thereof and a recess in the rearward part thereof, and an air hole leading from said recess at an angle to it and opening to the front face of the brick approximately at the base of said ridge, said hole being directed laterally with reference to the brick.
11. A furnace wall comprising a rear section and a front section with an air space between said sections, said front section including bricks each having a ridge projecting from the front face thereof, each of said bricks also having an air hole extending through it and opening to the front face thereof at one side of said ridge, said air hole extending at an inclination serving to direct air against the inclined surface of the ridge portion of a next adjacent brick.

OSCAR NYGAARD.
